UNITED STATES PATENT OFFICE.

PETER C. BURNS, OF CHICAGO, ILLINOIS, ASSIGNEE TO THE AMERICAN ELECTRIC COMPANY, OF CHICAGO, ILLINOIS, A CORPORATION OF ILLINOIS.

EXTENSIBLE SUPPORT.

1,109,038.

Specification of Letters Patent.

Patented Sept. 1, 1914.

Application filed May 8, 1913. Serial No. 766,277.

To all whom it may concern:

Be it known that I, PETER C. BURNS, a citizen of the United States of America, and resident of Chicago, Cook county, Illinois, have invented a certain new and useful Improvement in Extensible Support, of which the following is a specification.

My invention relates to improvements in extensible supports such as are employed for supporting telephone sets, lights or mirrors, etc. In bracket supports of this character as heretofore devised, it has been found difficult to provide a bracket which not only can be extended in a horizontal plane, but also can be extended at an upwardly inclined angle, to thus vary the height at which the telephone set, for example, is supported.

The object of my invention is to provide an extensible bracket which can be extended in a horizontal plane in the ordinary manner, and can also be raised so as to extend upwardly, and then be automatically locked in this raised position and cannot be unlocked until the bracket has been collapsed or contracted to a predetermined point.

A further object of my invention is to provide a yielding stop to take away the sudden jar occasioned by the sudden collapsing of the bracket from its raised position.

It is further found that when supports of this character are clamped on to the tubular telephone stand that they are apt to slide upwardly and thus come in contact with the telephone switch hook and lift this hook. To prevent this, I provide an arm which engages beneath the head of the telephone stand to prevent the clamp from rising to such an extent as to effect the switch hook.

These and other objects of my invention will be more readily understood by having reference to the accompanying drawings, in which—

Figure 1 represents a side elevation of my improved bracket, showing this bracket in extended form. Fig. 2 is a similar view showing the bracket contracted and supporting a telephone stand. Figs. 3, 4 and 5 are detail views.

My improved bracket consists of two series of links 7, 8, pivoted together to form

a well known "lazy tongs," the construction being such that these links can be extended or contracted in the well known manner. The outer end of the series of links 7 is pivotally connected to the clamp 9 mounted on the rod 10, while the inner end of this series of links is connected to the clamp 11 mounted on the supporting rod 12. The rod 10 carries the clamp 13 which is adapted to clamp the tubular telephone support 14, in the manner clearly shown in Fig. 2. Carried by this clamp 13 is an upwardly extending finger 13^a which is adapted to engage beneath the beading on the telephone set 14, in the manner clearly indicated, to prevent this clamp from sliding upward and thus engaging the switch hook (not shown).

The outer end of the series of links 8, instead of being connected directly to the clamp 15 on the rod 10, is connected to this clamp through a pivoted lever 16, this construction being such that the clamp 15 can be made rigid with the rod 10, as this pivoted lever connection obviates the necessity of a sliding bearing. The inner end of this series of links 8 is likewise pivotally connected with the clamp 17. This pivotal connection consists of the arm 18 provided with a slot 19. This slot is provided with an enlarged upwardly curved end portion 20, and the lower side 21 of the arm is likewise bent inward slightly, so as to form a spring or yielding stop in the manner which will hereinafter be more fully set forth. Rigidly mounted on the link 8 is a stud 22, which stud engages within the slot 19 of the arm 18. This stud has a flattened face 23.

When the bracket is in closed position, as indicated in Fig. 2, the stud 22 is at the inner end of the slot 19, and the bracket can then be extended or contracted in a horizontal plane, as indicated in dotted lines in Fig. 1, without the stud moving any appreciable distance within the slot 19. When it is desired, however, to support the telephone in the raised position shown in full lines in Fig. 1, it is merely necessary to draw upwardly on the stand 14, and the stud 22 slides along the slot 19 permitting the lower end of the inner link 8 to draw away from the supporting rod 12. When the stud 22 has reached the end of the slot 19, the curved portion of this stud 22 engages with the up-

wardly curved enlarged end portion of this slot, in the manner clearly shown in Fig. 4, the link 18 dropping downward by gravity to engage the stud in this manner. The bracket is thus securely locked in raised position—that is, the bracket cannot swing downward, as the engagement of the stud 22 in the end of the slot 19 forms a rigid connection between the link 8 and the supporting rod 12. When the bracket is collapsed, the angle of the inner link 8 varies, as this link pivots around its pivotal point of connection with the corresponding link 7, and thus the angle of this link varies with respect to the arm 18. When the bracket is in extended position, the inner link 8 is in substantially the angular position shown in Fig. 3, while when the bracket has been contracted this link is in substantially the position shown in Fig. 4. The stud 22 being integral with this link likewise, therefore, rotates with respect to the arm 18. As the stud thus rotates with respect to this arm, the curved portion of the stud gradually moves out of engagement with the enlarged end portion 20, and when the flat face has been brought into the position indicated in Fig. 4, it will be seen that the stud is free to move downward along this slot. The point at which this release occurs is preferably adjusted so that this downward movement does not occur until the bracket has been moved to substantially its closed position. As the stud moves along the slot, this movement is retarded on account of the arm 21, which, being bent inward, causes frictional engagement between the sides of the slot and this stop, and in this manner any excessive jar, due to the weight of the telephone, is obviated.

It will thus be seen that I have devised a very efficient form of bracket, one in which the bracket can be extended or contracted in a plane at right angles to the support, and which can also be extended at an upwardly inclined angle, means being provided for automatically locking the support in this raised position, and to automatically unlock the same after the support has been contracted. Furthermore, the spring arm 21 provides very efficient means for preventing any excessive shocks through the careless handling of the bracket.

While I have illustrated and described one specific embodiment of my invention, it will, of course, be understood that I do not wish to be limited to the exact construction shown and described, as various modifications will readily suggest themselves to those skilled in the art.

What I claim as my invention is:

1. In a device of the class described, a support, an extensible bracket secured to said support and adapted to be extended and contracted in a plane at right angles to

said support, means for permitting said support being extended at an upwardly inclined angle, means for automatically locking the extended support in this raised position, and means for automatically releasing this locking means when the support is contracted. 70

2. In a device of the class described, a support, lazy-tongs pivotally connected to said support, adapted to be extended and contracted in a horizontal plane, means for permitting said lazy-tongs to be extended to an upwardly inclined angle, and means for automatically locking said lazy-tongs in said extended and raised position so as to prevent 75 them from swinging downward. 80

3. In a device of the class described, a support, lazy-tongs pivotally connected to said support, adapted to be extended and contracted in a horizontal plane, means for permitting said lazy-tongs to be extended to an upwardly inclined angle, means for automatically locking said lazy-tongs in said 85 extended and raised position so as to prevent them from swinging downward, and 90 means for releasing said locking means by the movement of said lazy-tongs as they are brought into closed position. 95

4. In a device of the class described, a support, an extensible bracket secured to said support and adapted to be extended and contracted in a plane at right angles to said support, means for permitting said bracket being extended at an upwardly inclined angle, means for automatically locking the 100 extended bracket in this raised position, means for automatically releasing this locking means when the bracket is contracted, and means for then retarding the downward movement of said bracket. 105

5. In a device of the class described, lazy-tongs, a support, pivotal connections at one point between said support and said lazy-tongs, adjustable connections at a second point, said adjustable connections comprising a slotted arm pivotally connected to said support, a stud carried by said lazy-tongs and engaging said slot, said connection permitting said lazy-tongs to be raised into extended position, an enlarged end portion 110 on said slot adapted to be engaged by said stud for locking said tongs in this raised position, and means for automatically releasing said stud from said enlarged end portion of said slot when said lazy-tongs 115 are contracted. 120

6. In a device of the class described, lazy-tongs, a support, pivotal connections at one point between said support and said lazy-tongs and adjustable connections at a second point, said adjustable connections comprising a slotted arm pivotally connected to said support, and a stud carried by said lazy-tongs and engaging said slot, said connection permitting said lazy-tongs to be 125 130

- raised into extended position, an enlarged end portion on said slot adapted to be engaged by said stud for locking said tongs in this raised position, said stud being provided with a flat face to permit said stud to be released from the enlarged end portion of the slot when said lazy-tongs are contracted. 45
7. In a device of the class described, a support, an extensible bracket secured to said support and adapted to be extended and contracted in a plane at right angles to said support, means for permitting said support being extended at an upwardly inclined angle, means for automatically locking the extended support in this raised position, means for automatically releasing this locking means when the support is contracted, and means for then retarding the downward movement of said bracket. 50
8. In a device of the class described, lazy-tongs, a support, pivotal connections at one point between said support and said lazy-tongs, adjustable connections at a second point, said adjustable connections comprising a slotted arm pivotally connected to said support, a stud carried by said lazy-tongs and engaging said slot, said connection permitting said lazy-tongs to be raised into extended position, an enlarged end portion on said slot adapted to be engaged by said stud for locking said tongs in this raised position, and means for automatically releasing said stud from said enlarged end portion of said slot when said lazy-tongs are contracted, said slot being provided with a yielding side engaging said stud to retard the downward movement of said bracket. 55
9. In a device of the class described, lazy-tongs, a support, pivotal connections at one point between said support and said lazy-tongs and adjustable connections at a second point, said adjustable connections com- 60
- prising a slotted arm pivotally connected to said support, a stud carried by said lazy-tongs and engaging said slot, said connection permitting said lazy-tongs to be raised into extended position, an enlarged end portion on said slot adapted to be engaged by said stud for locking said tongs in this raised position, said stud being provided with a flat face to permit said stud to be released from the enlarged end portion of the slot when said lazy-tongs are contracted, and said slot being provided with a yielding side engaging said stud to retard the downward movement of said bracket. 65
10. An extensible bracket comprising lazy-tongs and a support, a swinging link supporting and connecting one end of said lazy-tongs to said support and allowing extension and contraction of the same, said link having a sliding connection with said lazy-tongs, whereby one end of said lazy-tongs may swing away from said support. 70
11. In a device of the class described, a support, an extensible bracket carried thereby, a clamp carried by said bracket and adapted to engage a tubular telephone support, and an upwardly extending finger carried by said clamp, adapted to engage beneath the head on said telephone support. 75
12. In a device of the class described, a support, an extensible bracket secured to said support and adapted to be extended and contracted in a plane at right angles to said support, means for permitting said bracket being extended at an upwardly inclined angle, and means for then retarding the downward movement of said bracket. 80

Signed by me at Chicago, Illinois, this 29 day of April 1913.

PETER C. BURNS.
